Application August 1, 1945, Serial No. 608,320

2 Claims. (Cl. 315—5)

1

This invention relates generally to electrical apparatus and more particularly to an electronic device for generating oscillations at high frequencies.

Amplitude modulated electronic vacuum tubes have long been used as generators of radio frequency oscillations. However, for operation at frequencies so high that the transit time of the electrons from cathode to plate becomes appreciable with respect to the duration of a cycle, efficiency drops considerably and difficulty is encountered in maintaining oscillations. This is due in main to the shift in phase between the plate current and the grid voltage and decrease in effective reactance between grid and cathode.

A partial solution to the problem of operating at such high frequencies has been found in velocity-modulated electronic tubes, the operation of which depends upon modulating the speed of the electrons passing through it and thus bunching electrons.

Great difficulties have been encountered in the use of this type of tube generally known as and hereinafter referred to as klystrons because they are very critical to adjust since the tuning and spacing of the cavities are interdependent.

An improvement of the first developed type of klystron is the reflex klystron in which the same set of grids is used for both bunching and catching the electrons and a negative repeller plate is provided to force the electrons to retrace their paths.

There still remain in these reflex klystrons many undesirable characteristics, such as frequency drift and instability, dead-spots in the tuning range, and undesired and troublesome operation on spurious modes. In the reflex klystron frequency drift and instability arise from the numerous contacts required between prefabricated parts and from the reflection of reactances into the principal cavity from auxiliary cavities and resonating loops or probes. Despite most careful manufacturing processes and well thought out design, it has been found impossible in the conventionally used waveguide type of cavity to eliminate all of these objectional features.

Operation on spurious modes is due to the fact that at very high frequencies the principal cavity itself is usually so large with respect to the corresponding wavelength and is of such configuration as to readily permit more than one mode of operation. The oscillation of a cavity results in a particular voltage and current distribution within that cavity resulting in magnetic fields containing the oscillatory energy. The configuration of

2

these fields within a cavity can take many forms; that is, a cavity can usually permit oscillations at several fundamental frequencies as well as at harmonics of the fundamentals, depending on the manner in which the cavity is energized and the shape and dimensions of the cavity. Thus the electromagnetic fields within a cavity can assume many patterns; each of these patterns is called a mode.

10 The frequency range over which reflex klystrons including a waveguide type of cavity may be tuned has been limited because with the cavities used tuning has been non-linear and asymptotic in characteristic. Further, since oscillations at two modes at the same frequency are possible for a given position of the tuning means, the tuning means may upon further adjustment follow the wrong mode.

15 It is an object of the present invention to provide a velocity-modulated electronic tube in which these disadvantages are eliminated by reducing the number of critical contacts, by decreasing the dimensions of the resonant cavity, and by improving the configuration of the cavity. There results a tube which may be tuned over a range of high frequencies with stability at any chosen operating frequency and without any frequency within its frequency range, at which there is a failure of oscillation.

20 It is a further object of the present invention to provide a velocity-modulated tube which contains tuning means having a substantially linear characteristic thus extending the tunable range over the prior art.

25 30 An advantage of the present invention is that a variety of types of plunger, such as the choke type, may be used.

35 These objects are accomplished by means of a single coaxial cavity arranged to surround the electron stream and to have its frequency determining dimension parallel to the main electron stream. The cavity formed between inner and outer conductors can readily be chosen to have all major dimensions, except the frequency determining dimensions, so small that any spurious mode of operation arising therefrom would be at frequencies much higher than those of the operating range. The cavity is readily adaptable to the use of tuning means having substantial linear change in frequency with respect to its movement.

40 45 Frequency stability at the chosen frequency of operation is achieved by the simplicity of construction of devices made by applying the principles of the present invention. In such devices there are not necessary any auxiliary elements

associated with the device, thus there is nothing present capable of resonance within the operating frequency range. In practice it has been found desirable to assemble the device in two major units.

Other objects, features, and advantages of this invention will suggest themselves to those skilled in the art and will become apparent from the following description of the invention taken in connection with the accompanying drawing which is a cross-sectional view of a device representing a preferred embodiment of the invention.

A coaxial cavity resonator 10 is formed by two concentric hollow cylinders consisting of outer cylinder 11 and inner cylinder 12. Between these two cylinders is a plunger 13 which is in the form of an annular ring and which is movable to change the length of cavity resonator 10 thus changing the operating frequency. At the end of cavity resonator 10 opposite plunger 13 there are two grids 14 and 15, each formed by a circular washer having small concentric orifices 14a and 15a. The washers forming grids 14 and 15 preferably have flanged portions 14b and 15b surrounding orifices 14a and 15a for purposes of mechanical strength.

Grid 14 is at its outer edge attached to and makes electrical contact with the end of outer coaxial conductor 11. Similarly grid 15 is attached to and makes electrical contact with the end of inner coaxial conductor 12.

Repeller electrode 16 which is made in the shape of a hollow cylinder with an aperture 16a to give maximum concentration of returning electrons is mounted within inner conductor 12 in close proximity to grid 15. A central conductor 17 attached to repeller 16 and terminating in a terminal cap 18 provides means for applying the desired direct current potential to repeller 16. Central conductor 17 for a portion of its length 40 is surrounded by an insulating material 19 of low dielectric loss.

The cathode assembly consists of a heater element 20, cathode 21, and beam forming cylinder 22. Connections to these electrodes are made to pins 23, extending through terminal base 24 of conventional design.

The space between grids 14 and 15 should have a length less than one-half the wavelength corresponding to the highest frequency in the range 50 of operation for which the device is designed.

The evacuated portion of the tube is enclosed by glass envelope 25. Envelope 25 is sealed to terminal base 24 and extends into inner conductor 12 a sufficient distance to enclose repeller 16. Envelope 25 is sealed to conductor 17 where that conductor passes through it. Seals also are made in envelope 25 where grids 14 and 15 pass through it.

An inductive coupling loop 26, or any well known means such as a capacity probe, is attached at one end to outer coaxial conductor 11 and at its other end through hole 27 provided for that purpose in outer coaxial conductor 11 to any conventional connecting means such as 28.

The physical arrangement of the components of this invention favors the prefabrication of the device in two major units. The part of the device inclosed in and integral with glass envelope 25 is made as one unit. This includes besides those parts entirely within the envelope 25, grids 14 and 15, inner conductor 12, conductor 17, insulating material 19, and terminals 18 and 24. The second unit consists of outer coaxial con-

ductor 11, tuning plunger 13, and coupling loop 26.

Outer conductor 11 is maintained at ground potential and means are provided for maintaining cathode 21 and repeller 16 at direct current potentials negative to ground with repeller 16 more negative than cathode 21.

In operation, electrons are emitted at cathode 21 and are kept in a narrow beam by beam forming cylinder 22. These are attracted through orifices 14a and 15a by the positive potentials, with respect to cathode 21, on grids 14 and 15. Electrons pass through these orifices and into the cavity formed in repeller 16 whence they return to cathode 21. On each trip some of the electrons will be absorbed by grids 14, 15 and their energy dissipated as heat but sufficient pass through orifices 14a and 15a properly bunched and in right phase relationship to set up an oscillating magnetic field in the drift space between grids 14 and 15. The presence of grids 14 and 15 in this oscillating field causes cavity resonator 10 to oscillate at its resonant frequency. The resulting radio frequency field between grids 14 and 15 due to oscillation of cavity resonator 10, velocity-modulates the electrons in their initial flight through the drift space. Upon the return trip of electrons toward cathode 21, caused by the negative charged repeller electrode 16, which, since it is located within inner coaxial conductor 12, is protected from the intensity of that field, the velocity-modulated electron beam will, if in the proper phase relationship, transfer additional energy to cavity resonator 10, thereby reinforcing existing oscillations.

Oscillations in cavity resonator 10 may be set up in accordance with any mode, that is, at any frequency at which the dimensions and configuration of cavity resonator 10 will permit. It is important that in the cavity formed by the arrangement hereinabove described there is no dimension, other than the length determined by the position of plunger 13, within the frequency operating range at which this cavity can oscillate. The reason for this is that all other dimensions of cavity resonator 10 are appreciably less than that of its frequency determining dimension. It is a feature of this invention that the commonly used type of cavity resonator is replaced by a coaxial cavity resonator which permits not only choice of relative dimensions as herein taught, but also provides a cavity resonator the wavelength of which is substantially a linear function of the position of the plunger. Thus under proper operating conditions any spurious oscillations that could occur would be at frequencies outside those in the operating range of the oscillator and would not cause failure of oscillation—dead-spots—within the range. For the above dimensional relationship to be insured over a wide band of high operating frequencies, the use of a coaxial conductor is necessary.

Energy at the desired frequency may be extracted from cavity resonator 10 by use of an inductive coupling loop 26 which should be of such physical size as to be nonresonant within the range of operating frequencies. In order to maintain oscillations, loop 26 should be placed in an electromagnetic field of a desired density, or angularly disposed with respect to the magnetic lines of the field so that the proper impedance match and loading is reflected back into the cavity resonator.

While there has been here described what is at present considered to be the preferred embodi-

ment of the invention, it will be obvious to those skilled in the art that various changes and modifications may be made therein without departing from the spirit or scope of the invention.

What is claimed is:

1. A reflex velocity-modulated electron oscillator having first and second component units adapted to be engaged together, said first unit comprising: a cylindrical evacuated envelope containing, in spaced axial succession, an electron gun for generating a beam of electrons, a first apertured disc, a second apertured disc, the distance between said first and second discs being less than one-half the wavelength corresponding to the highest frequency within the range of operation of said reflex electron oscillator, said first and second discs being circular in shape and radially extending without said envelope, the diameter of said first disc being larger than that of said second disc, said second disc comprising a cylindrical element of a given diameter axially aligned with said electron gun, said cylindrical element having an outwardly extending flange at one end and a base at the opposite end with an opening whose diameter is less than said given diameter, an electron repeller, said repeller being disposed within said cylindrical element and having the shape of a hollow cylinder with a central aperture therein, the diameter of said repeller being less than said given diameter, said repeller providing a maximum concentration of returning electrons, and an axial central conductor having one end attached to said repeller within said envelope and having its other end extending axially without said envelope; a dielectric member surrounding said other end of said central conductor; a terminal cap connected to said other end of said conductor and to said dielectric member for providing a connection to which a potential that is negative with respect to said discs may be applied to said repeller; and a hollow cylinder coaxial with said central conductor and forming an integral part with the flange of said second disc, said cylinder having a uniform cross-section with a diameter substantially equal to that of said second disc; and said second unit comprising: a hollow cylinder coaxial with and disposed about the first-named cylinder, having a uniform cross-section with a diameter substantially equal to that of said first disc, and being in contact with said first disc, said cylinders forming a single cavity resonator therebetween such that the effective axial length of said resonator with respect to the remaining resonator dimensions is large and is the main determinant of the frequency of oscil-

lation of said reflex oscillator; a loop probe inserted within the second-named cylinder to extract energy from said cavity resonator; and an annular plunger slidably engaging both said cylinders within said resonator, said plunger serving to linearly vary the effective axial length of said cavity resonator and thus similarly vary the frequency of said reflex oscillator.

2. A reflex velocity-modulated electron device comprising, as a single unit: a cylindrical evacuated envelope containing, in spaced axial succession, an electron gun for generating a beam of electrons, a first apertured disc, a second apertured disc, the distance between said first and second disc being less than one-half wavelength corresponding to the highest frequency within the range of operation of said reflex electron device, said first and second discs being circular in shape and radially extending without said envelope, the diameter of said first disc being larger than that of said second disc, said second disc comprising a cylindrical element of a given diameter axially aligned with said electron gun, said cylindrical element having an outwardly extending flange at one end and a base at the opposite end with an opening whose diameter is less than said given diameter, an electron repeller, said repeller being disposed within said cylindrical element and having the shape of a hollow cylinder with a central aperture therein, the diameter of said repeller being less than said given diameter, said repeller providing a maximum concentration of returning electrons, and an axial central conductor having one end attached to said repeller within said envelope and having its other end extending axially without said envelope; a dielectric member surrounding said other end of said central conductor; a terminal cap connected to said other end of said conductor and to said dielectric member; and a hollow cylinder coaxial with said central conductor and attached to the flange of said second disc, said cylinder having a uniform cross-section with a diameter substantially equal to that of said second disc.
